UNITED STATES PATENT OFFICE.

GEORGE A. DOBYNE, OF ST. LOUIS, MISSOURI, ASSIGNOR TO CHAMPION SHOE MANUFACTORY COMPANY, OF ST. LOUIS, MISSOURI, A CORPORATION OF MISSOURI.

WELT-SHOE.

1,251,354.

Specification of Letters Patent. Patented Dec. 25, 1917.

Application filed January 4, 1915. Serial No. 515.

To all whom it may concern:

Be it known that I, GEORGE A. DOBYNE, a citizen of the United States, and residing at St. Louis, in the State of Missouri, have invented a certain new and useful Improvement in Welt-Shoes, of which the following is a specification.

This invention relates to shoes, and more particularly, to shoes of the welt type.

10 In the ordinary Goodyear-welt shoe, the upper is lasted against a channel lip on the insole, the welt is attached by a seam passing through the welt, upper and channel lip, and the outsole is sewed to the welt. This 15 method of fastening the welt requires an insole of high grade leather, otherwise the welt seam, which really holds the upper, insole and outsole together, will tear. It is, therefore, impractical to use low or medium 20 grade insoles or welting in Goodyear-welt shoes. Many attempts have been made to attach a welt to a McKay lasted shoe by a metallic seam passing through the welt and upper and directly through the insole, but 25 without success. When using the ordinary nail with low or medium grade welting and insoles, the seam was not water tight and would readily tear, as the fasteners would tear through the soft insole and welt. When 30 a staple fastener was used the resultant sole was stiff, and the inside of the shoe was rough. Now, in addition to strength of seams, a shoe should have the characteristics of flexibility, and non-protrusion of points 35 through the insole.

Some of the objects of this invention, therefore, are to construct a shoe of the welt type, in which the welt is attached to the lasted upper by a metallic fastener seam, 40 which permits the use of low and medium grade insoles and welting, and which is characterized by maximum strength of seams, flexibility of sole, and a smooth insole surface.

45 Further objects will appear from the detail description taken in connection with the accompanying drawing, in which:

Figure 1 is a side elevation of a shoe embodying this invention;

50 Fig. 2 is a bottom view of the shoe before the outsole is attached;

Fig. 3 is a section on the line 3-3, Fig. 2;

Fig. 4 is a section similar to Fig. 3, but with the outsole in place;

55 Fig. 5 is a section on the line 5-5, Fig. 3;

Fig. 6 is a section on the line 6-6, Fig. 4;

Fig. 7 is an enlarged view of Fig. 6;

Fig. 8 is a perspective view of the fastener; and,

Fig. 9 is an enlarged view of the point of 60 the fastener.

Referring to the accompanying drawing, 10 designates the upper, 11 the insole, 12 the outsole, and 13 the heel of a shoe. The upper is lasted over the insole in accordance 65 with the usual McKay practice. The welt 15 is secured to the upper by a metallic fastener seam comprising metallic fasteners 18 having laterally projecting heads 19 and points 20. The point 20 of the fastener is 70 turned or deflected slightly to make an abrupt bend at the extreme end thereof, as shown in Fig. 9. This is accomplished in the process of forming the fastener, and its object is to so form the point that the direction 75 of the clench will be accurately controlled, whereby the point will be clenched in a predetermined direction by the clenching anvil. This fastener is shown and described in U. S. Patent #1,072,213, September 2, 80 1913. In the former fastener, however, the head was of a bevel form, so as to countersink in the shoe sole. In this construction, however, the head 19 extends laterally from the shank for a distance equal to from one 85 and one-half to three times the thickness of the shank. The fastener is driven from the welt side, through the welt, upper and insole, with the point clenched and turned 90 back on the insole, and with the laterally 95 projecting head engaging the welt, as shown in Fig. 7. The fasteners are so inserted that the heads and clenched points will project in the same direction, and in a direction along the seam, as shown in Figs. 2, 5 and 6. 95 The outsole is secured in position by means of a seam 21, which may be a lock stitch seam, and the space between the outsole and insole is preferably filled with the usual cork filling 22.

100 It will, therefore, be seen that, in this shoe, the welt is attached by a metallic fastener seam, comprising fasteners passing through the welt, upper and insole, with the heads engaging the welt, and the clenched points turned back into the insole, as shown in Fig. 7. Where the usual head is used, such, for instance, as shown in the patent referred to, this head will be countersunk, and, in doing 105 so, will start to tear or disrupt the material. 110

Now, since the outer layer of material, which has been condensed by the rolling processes, etc., is stronger than the interior fibers, a tear once started will easily give. It is for this reason that a countersunk head which sinks or tears the fibers on the surface of the leather will readily tear out. Now, in accordance with this invention, the head 19 projects laterally from the shank a sufficient distance so that the driving of the fastener through the material will cause this head to clamp and compress the material without, however, tearing it. While, therefore, the head is somewhat countersunk, it does not actually enter the material, but simply carries the material around the head with it by a compressive action. The outer layer of fibers are, therefore, maintained intact, so that the total amount of material in the welt is under the fastener head. This, of course, results in a maximum strength material, and, moreover, results, on account of the clamping action, in an exceedingly tight seam.

In referring to Fig. 7 it will be noted that the point of the nail is clenched back into the insole. In the formation of the clench, the deflected point will be turned toward the shank of the fastener. Moreover, when the deflected point of the nail strikes the clenching anvil it will itself be bent laterally, so that when it turns back into the insole it will curl toward the shank. This will give the clenched point the effect of fish hook anchorage, the laterally deflected point acting as a barb to prevent the clenched point from working upwardly above the upper face of the insole. The nail is thus supported in the sole against movement either upwardly or downwardly.

A shoe sole must be capable of being flexed inwardly, and must, therefore, be flexible when bent in that direction. It need not, however, be very flexible in the other direction, that is, when flexed outwardly. In a laminated structure comprising the insole, upper and welt fastened together by the metallic fastener seam, the flexing of the sole

will not cause an elongation of the fibers of the welt, but merely a compression of the fibers at the insole. The compression is, however, negligible. Now, it will be noted that, since the heads of the fasteners do not enter the welt, and do not retain any part thereof, the welt fibers are just as free to elongate as if the fasteners were not present. Moreover, the arrangement in which the heads as well as the clenched points extend along the seam further enhances the flexibility of the sole in a direction along the seam, as the fasteners will, thereby, not interfere or restrict the flexure of the sole. The resilient sole will, therefore, be exceedingly flexible. Furthermore, the arrangement of the laterally projecting head engaging and clamping the welt will not only produce a tight seam, but a seam which has great strength. The clenched point will not only form a smooth insole, but these points, being anchored in the insole, will not work up therethrough.

70

It is obvious that various changes may be made in the details of construction without departing from the spirit of this invention. It is, therefore, to be understood that this invention is not to be limited to the specific details shown and described.

Having thus described the invention, what is claimed is:

A shoe comprising an upper, an insole, a welt, a metallic fastener seam for attaching said welt comprising headed metallic fasteners passing through the welt, upper and insole with the heads engaging and bearing upon the surface of the welt and with the points clenched on the insole, the head of each fastener projecting laterally from its shank an amount sufficient to firmly clamp and compress the welt but without rupturing the fibers thereof, and an outsole attached to said welt.

90

In testimony whereof I affix my signature in the presence of these two witnesses.

GEORGE A. DOBYNE.
